UNITED STATES PATENT OFFICE.

ARTHUR R. WEIS, OF HUNTINGTON PARK, CALIFORNIA, ASSIGNOR OF ONE-HALF TO
PACIFIC PUMP WORKS, OF HUNTINGTON PARK, CALIFORNIA, A CORPORATION OF
CALIFORNIA.

DEEP-WELL COLUMN JOINT.

Application filed June 1, 1927. Serial No. 195,683.

This invention relates to turbine irrigation pumps, and is an improvement on my invention embodied in my patent application entitled Oil tube tensioning means, filed August 19, 1926, Serial No. 130,327.

A common form of turbine irrigation pump has a pump-section placed near the lower end of a well and attached to the lower end of a column or discharge-pipe. The discharge-pipe is extended into the well from the surface of the ground, and a pump-head is mounted at the surface of the ground to which the discharge-pipe is attached. Extending from the pump-head to the pump-section is a pump-shaft, by means of which the pump-section is operated, and surrounding the pump-shaft is an oil-tube which retains lubrication for pump-shaft bearings which are supported by the oil-tube. It is common practice to attach the lower end of the oil-tube to the upper part of the pump-section and to place a tension on it by means of a nut located at the upper end thereof and in the pump-head. It is highly desirable for various reasons to maintain a substantial tension on the oil-tube. One reason is to keep the oil-tube absolutely concentric so that the bearings will support the pump-shaft in exact axial alignment so that there will be no whipping of the shaft. The present manner of applying tension to the oil-tube is not entirely satisfactory. A considerable degree of tension is applied to the upper end of the oil-tube, but by reason of the weight thereof the oil-tube has less tension at the lower end. One big objection to and deficiency of this method of applying tension is that the initial tension very often diminishes, because of the great distance and many joints between the upper and lower ends, so that it is possible for the oil-tube to move out of concentricity and for the pump shaft to whip.

It is one of the important objects of this invention to provide a pump of the character mentioned in which tension is applied to the oil-tube at intervals between the upper and lower ends.

Another object of the invention is to provide a novel form of tensioning-joint, per se.

Other objects and advantages of the invention will be made evident hereinafter.

In the following description I illustrate the invention applied to a particular design of irrigation turbine pump. My invention,

however, may be used in various types of pumps and I, therefore, do not wish to have my invention limited to the type of pump shown but wish it to be construed in the breadth of the appended claims.

Referring to the drawing in which I illustrate my invention:

Fig. 1 is a vertical view, partially sectioned, of a pump embodying the features of this invention.

Fig. 2 is an enlarged vertical section of a tensioning-joint of the invention.

Fig. 3 is a section taken on the line 3—3 of Fig. 2.

Referring in detail to Fig. 1 of the drawing, a well casing 11 is extended into a well. Mounted on a foundation 12 at the upper end of a well is a pump-head 13 and extended downward from the pump-head 13 into the well is a column-pipe or discharge-pipe 14. Secured to the lower end of the discharge-pipe 14 is a pump-unit 15, this pump-unit being situated near the lower end of the well below the water-level thereof. The pump-section 15 has impellers 17 which are mounted on a pump-shaft 18. The pump-shaft 18 extends upward through the discharge-pipe 14 and is drivably connected with a motor 19 which forms a part of the pump-head 13.

Surrounding the pump-shaft 18 is an oil-tube 20 which carries bearings 21 in which the pump-shaft 18 is journaled. The lower end of the oil-tube 20 is secured at 23 to the upper part of the pump-unit 15. The upper end of the oil-tube 20 is threadedly secured to a packing member 27 which is supported by a discharge casting 28 of the pump-head 13.

The oil-tube 20 is supported at intervals between the upper and lower ends thereof by tensioning-means or tensioning-joints best illustrated in Figs. 2 and 3. The discharge-pipe 14 is made up of lengths of pipe 30 which are threaded at the ends thereof and which are secured together by couplings 31. Adjacent ends 32 of the lengths of pipe 30 engage opposite faces of a ring 33 which forms a part of a tensioning-spider 34. The spider 34 is rigidly secured in place by the engagement of the end faces 32 of the pipe 30 with the side faces of the ring 33. Extended radially inward from the ring 33 is a plurality of webs 35. Formed integral with the webs 35 at the inner ends thereof

2

is a hub 36 which is provided with a smooth cylindrical bore 37. The oil-tube 20 is composed of lengths of tubing 39 which are threaded at the ends thereof. The threaded ends of the tubing 39 are screwed into a nut-coupling 40 which is disposed directly above the hub 36. The upper part of the hub 36 is provided with an annular countersunk seat 41 which is engaged by the end 10 of a cylindrical projection 42 formed on the lower end of the nut-coupling 40. The nut-coupling 40 is screwed downward on the upper end of the lower length of tubing 39 to such an extent that it is resting on the hub 36 and is pulling upward on the lower length of tubing 39 so that a tension is placed on this tubing 39. A bearing 21 is placed at each tensioning-joint. Each bearing 21 extends into the upper end of one of 15 the lengths of tubing 39. The upper end of each bearing 21 is provided with a cylindrical projection 45 which extends outward into a position between adjacent ends 46 of adjacent lengths of tubing 39. The ends 46 of 20 the lengths of tubing 39 tightly engage the cylindrical projection 45 and clamp the bearing 21 rigidly in place.

The manner in which the tension is placed on the oil-tube 20 may be best understood 30 from a description of the manner of assembling the pump.

Referring to Fig. 2 the lower pipe 30 thereof and the lower length of tubing 39 are first assembled. The next operation is 35 to install the tensioning-spider 34. This is done by placing the spider at the upper end of the lower length of pipe 30, so that the ring 33 rests thereon and so that the hub 36 surrounds the upper end of the lower length 40 of tubing 39. The upper threaded end of the lower length of tubing 39 extends above the collar 36. The inner part which is assembled is the nut-coupling 40. The nut-coupling 40 is screwed onto the upper threaded end of the lower length of tubing 39 until 45 the cylindrical projection 42 thereof engages the annular seat 41. After this engagement has been made it will be seen that the nut-coupling 40 cannot move down any more, and that if the nut-coupling is rotated the upper end of the lower length of tubing 39 must move upward. The nut-coupling is 50 then turned, and the upper end of the lower length of tubing 39 is moved upward. In 55 view of the fact that the lower end of this tubing 39 is secured, a tension will be placed on it. The next step is to install the bearing 21. After the bearing 21 is placed, as shown in the drawing, the upper length of tubing 39 in Fig. 2 is screwed into the upper part 60 of the nut-coupling 40 so that the lower end 46 thereof engages the cylindrical projection 45 of the bearing 20. The upper length of pipe 30 in Fig. 2 is then screwed into the 65 coupling 31 so that the lower end 32 there-

of engages the ring 33 of the tensioning-spider 34, thus clamping it tightly in place. The other tensioning-joints of the column pipe are assembled in the same manner as the one shown in Figs. 2 and 3.

From the foregoing description it will be seen that the oil-tube 20 will have a uniform tension applied thereto throughout its entire length. In view of the fact that the tension is applied at every joint, this tension 70 will be permanent because there are no interposed joints which will give and diminish the original tension of the oil-tube. Ordinarily the length of the pipe 30 is about twenty feet; therefore, tension is 75 applied to the oil-tube at every twenty feet. It will be seen that the oil-tube will be absolutely concentric, and the bearings 21 will maintain the pump-shaft 18 in accurate 80 axial alignment so that there can be no 85 whipping and no attendant stresses which would bring about a premature breakage of the pump-shaft.

An important part of the invention is its 90 simplicity of construction. The spider 34 serves the purpose of centralizing the oil-tube and also serves as a support for the nut-coupling 40 which also serves a dual purpose. The nut-coupling 40 acts as a coupling for the lengths of tubing 39 and also 95 as a means for applying tension to them.

I claim as my invention:

1. In a pump construction of the class described, the combination of: guide means having a hub, said hub having an opening therethrough; means for supporting said guide means; a tube extended through the opening of said hub; a nut-coupling secured to the upper end of said tube, said nut-coupling being adapted to engage said hub and to place a tension on said tube; and a second tube located above said first-named tube and secured to said nut-coupling.

2. A combination as defined in claim 1 having: a bearing extended into one of said tubes; and a flange formed on said bearing, said flange extending between the ends of said tubes, thereby being secured in place.

3. A combination as defined in claim 1 in which said hub is provided with an annular seat, and in which said nut-coupling is provided with a cylindrical projection which engages said annular seat.

4. In a pump construction of the class described, the combination of: a column-pipe, said column-pipe consisting of lengths of pipe secured together by a coupling; a spider secured in said column-pipe between adjacent lengths of pipe, said spider having a concentric hub, said hub having an opening formed therethrough; a tube located in said column-pipe, the upper end of said tube extending through the opening of said hub; a nut-coupling screwed onto the upper end 120 of said tube, said nut-coupling engaging the 125

upper part of said hub and placing a tension on said tube; and a second tube screwed into said nut-coupling, said second tube being placed in axial alignment above said 5 first-named tube.

5. A combination as defined in claim 4 including: a bearing located in the upper end of said first-named tube; and an annular

flange formed on the upper part of said bearing, said annular flange being clamped 10 between adjacent ends of said tubes in such a manner that said bearing is held in place.

In testimony whereof, I have hereunto set my hand at Los Angeles, California, this 27th day of May, 1927.

ARTHUR R. WEIS.
